UNITED STATES PATENT OFFICE.

FRANK ARTHUR SIMONDS, OF GRAND RAPIDS, MICHIGAN.

METHOD OF HEATING BY STEAM.

No. 811,670.

Specification of Letters Patent.

Patented Feb. 6, 1906.

Application filed April 20, 1905. Serial No. 266,516.

To all whom it may concern:

Be it known that I, FRANK ARTHUR SIMONDS, a citizen of the United States, residing at Grand Rapids, in the county of Kent and State of Michigan, have invented certain new and useful Improvements in Methods of Heating by Steam; and I do hereby declare the following to be a full, clear, and exact description of the invention, such as will enable others skilled in the art to which it appertains to make and use the same.

My invention relates to improvements in methods of heating by steam; and its object is to improve the method described in my application filed April 29, 1904, Serial No. 205,567, on method and apparatus for steam-heating, so that the water will be more effectually reëvaporated in the low-pressure radiator; and it consists, essentially, of the feature of injecting the water into the low-pressure radiator at a point above the bottom thereof, whereby the water flows vertically in this second radiator before flowing horizontally toward the exit-opening and is thus caused to traverse a greater distance in the said radiator and is also divided and more effectually distributed over the surface thereof and is thus caused to more readily and completely evaporate or vaporize in the same.

The accompanying drawings illustrate a device adapted to practically illustrate my improved method.

Figure 1 is a side elevation of the device with a part broken away; Fig. 2, an enlarged detail of the trap for passing the condensed water from the high-pressure radiator to the low-pressure radiator and is shown in vertical section through the plane of the axis of the same.

Like numerals refer to like parts in both of the figures.

1 represents the high-pressure radiator to which steam is admitted from any suitable steam-line by means of the connection 24. In this radiator and under pressure the steam is condensed at a temperature depending upon the pressure carried in said radiator. The condensed water flows through the connecting-pipe 6 into the first chamber 7 underneath the bed-plate 18 and thence upward through an opening 9 in the bed-plate, where it accumulates within the case 3 until sufficient quantity is accumulated to lift the balanced valves 10 and 13. The water then escapes into the second chamber 7 and thence

upward through the pipe 4, whence it is discharged through the elbow 5 into the upper part of the low-pressure radiator 2, in which a materially lower pressure and temperature is maintained. This radiator 2 is connected at the bottom to form a continuous passage, as at 22, and at the top is also connected in like manner to form an upper continuous passage 23, and the elbow 5 is preferably opposite this upper passage and provided with a contracted opening, whereby the water is discharged into the upper ends of the various coils of the radiator and flows downward therethrough. Being thus divided and separated and flowing downward in the coils 2 it will be more effectually reëvaporated than when discharged directly into the passage 22 in the lower part of the radiator, as heretofore shown. In the latter event it is liable to flow directly to the outlet 25 and be only partially reëvaporated, or not at all. In this low-pressure radiator 2 the reëvaporated water again condenses by further parting with its heat and is drawn off at the pipe 25. To render the trap between the radiators convenient and operative, it is provided with a strainer 21 to abstract any solid particles of matter that may be in the condensed steam, which strainer is removed for cleaning through an opening closed by a plug 26. To balance the valves and allow air to escape from the upper part of the device when the valves are opened by the float, a central tube 12 extends through the axis of the float 11 and through the valve 16, with branch openings 14, adjustably closed by a rotative cap 15, surrounding the valve-stem 19. To adjust these valves on their seats, the tube 12 is divided and screw-threaded and surrounded by a screw-threaded band 20, and the valve 10 and stem 19 are provided with screw-driver nicks, whereby the same may be relatively rotated by removing the cap above the upper valve and the plug 17 in the bottom of the case and inserting suitable tools in said nicks.

The essential novelty herein shown consists of the modification of the method described in the application heretofore referred to of injecting the condensed hot water into the low-pressure radiator at a distance above the bottom thereof and allowing the same to flow downward therein, as herein described.

The trap herein shown is not made a part of this application, but is covered by a sepa-

rate patent numbered 783,238, dated March 28, 1905, and is shown only to illustrate the method disclosed herein.

Any suitable means for maintaining a different pressure in the radiators and permitting the water to pass would operate instead of the device shown.

Having thus fully described my invention, what I claim, and desire to secure by Letters Patent, is—

1. In a method of heating by steam by means of two or more radiators connected in series and in which different temperatures and pressures are maintained, the improved method of reëvaporating the water consisting substantially of conducting the condensed water from the bottom of the high-pressure radiator and discharging the same into the lower-pressure radiator at a point above the bottom of the same.

2. In a method of heating by steam, substantially as herein described, the improved method of reëvaporating the condensed water by taking the same from the bottom of the high-pressure radiator and discharging said

water into the top of the "low-pressure" radiator.

3. In a method of heating by steam by means of radiators connected in series, and in which different pressures and temperatures are maintained, the improved method of reëvaporating the condensed water consisting in discharging the same into the low-pressure radiator in a spray and above the bottom of the same.

4. The improved method of heating by steam comprising admitting the steam to a radiator under a certain pressure and abstracting heat therefrom until the steam is condensed to water, passing the water to a second radiator in which a materially less pressure is maintained and discharging the water into said radiator near the top thereof and opposite a horizontal passage therein.

In testimony whereof I affix my signature in presence of two witnesses.

FRANK ARTHUR SIMONDS.
